UNITED STATES PATENT OFFICE.

PIERRE VICTOR LÉON BELLANGER, OF PARIS, FRANCE.

PROCESS OF BREAKING STEEL BARS.

1,201,137.

Specification of Letters Patent. Patented Oct. 10, 1916.

Application filed March 21, 1916. Serial No. 85,694.

To all whom it may concern:

Be it known that I, PIERRE VICTOR LÉON BELLANGER, citizen of the Republic of France, residing at Paris, France, have invented a new and useful Process of Breaking Steel Bars, of which the following is a specification.

This invention relates to a physico-mechanical process of breaking steel bars of any cross-section and dimensions, without waste of metal. At a point in the length of the bar where it is to be broken, the bar is submitted to a very slight and quick action of a blow-pipe, the flame of which may be oxidizing. During the action of the said flame, there is produced in the metal a local physico-chemical change which modifies its properties. The metal becomes brittle at the point thus treated, along a very limited zone, the width of which can be extremely small. The flame of the blow-pipe should preferably have the shape of a lance-head, that is to say flat and pointed. The width of the flame is applied in a direction normal to the length of the bar, and the latter is acted upon only by the point of the flame.

The molecules of the metal lose their elasticity, and the bar can be broken cleanly without the condition of the metal being in any way modified in the neighborhood of the point of attack.

It is not necessary that the notch made transversely at one point upon the periphery of the bar is a deep one, the fusing temperature to which the metal is subjected is about 700° C.

The bar is placed on two supports at a suitable distance apart; and a hard cutter, arranged transversely of the bar and above the point attacked, is caused by pressure or a blow to produce a clean break at the de-

sired point. The fracture shows an absolutely flat section, normal to the longitudinal axis of the bar, without tearing and without waste of metal.

In the accompanying drawing: Figure 1 is a section through the bar after being notched by the flame of the blow-pipe. Fig. 2 illustrates the bar supported, and Fig. 3 shows the bar bent under the action of the breaking tool.

a designates the notches created by the flame of the blow-pipe.

b and *c* are two supports upon which the bar rests intermediate its ends, and *d* is the breaking or cutting tool which is guided against the bar at the side opposite to the notch *a*.

Having now particularly described and ascertained the nature of my said invention and in what manner the same is to be performed, I declare that what I claim is:

1. A process of breaking steel bars, consisting in subjecting the bar to the action of an oxidizing flame for modifying the molecular structure of the metal at the point where the bar is to be broken, and finally breaking the bar at the place treated by said flame by subjecting it at the opposite side to the action of a breaking tool, substantially as described.

2. A process of the character described, consisting in subjecting the bar to be broken to the action of a flat and knife-shaped oxidizing flame transversely to the longitudinal axis of the bar and to a hard blow at a point located diametrically opposite to the place acted upon by said flame.

In testimony whereof I affix my signature in presence of two witnesses.

PIERRE VICTOR LÉON BELLANGER.
